UNITED STATES PATENT OFFICE.

JOHN P. NAUGHTON, OF LAWRENCE, MASSACHUSETTS.

ARCH-SUPPORTER FOR SHOES.

No. 899,182.

Specification of Letters Patent.

Patented Sept. 22, 1908.

Application filed November 16, 1907. Serial No. 402,516.

To all whom it may concern:

Be it known that I, JOHN P. NAUGHTON, a citizen of the United States, residing at Lawrence, in the county of Essex and State of Massachusetts, have invented new and useful Improvements in Arch-Supporters for Shoes, of which the following is a specification.

This invention is an improved arch supporter for boots and shoes and comprises a heel having a forwardly extending arm under the shank of the boot or shoe, to support the arch of the foot, and a metallic spring embedded in the arm and serving to reinforce the same and render said arm elastic, as hereinafter described and claimed.

This invention is an improvement on the arch supporter for which I made application for Letters Patent of the United States, 20 Aug. 21, 1907, Serial No. 389,571.

In the accompanying drawings, Figure 1 is a perspective view of a shoe provided with a heel having an arched supporting arm in accordance with my invention. Fig. 2 is a 25 longitudinal sectional view of the rear portion of the same. Fig. 3 is a detail perspective view of the spring reinforced for the arch-supporting arm.

In accordance with this invention, the 30 heel 1, which may be of any suitable shape and is made of layers of leather, or other suitable material is formed at its front side, at the center thereof, with a forwardly extending arm 2 to bear under and the upper 35 side of which conforms to the contour of the bottom of the shank 3 of the boot or shoe, the said arm extending from the heel to the sole and bearing under and being attached to the shank, so that it forms a support for 40 the arch of the foot and prevents the breaking down of the arch. The under side of the 45 said arch supporting arm 2 is flat and comes in contact with the floor or other supporting surface so that the said arm is enabled to support the arch of the foot.

To strengthen the construction of the arch supporting arm and render the same elastic, to promote the comfort of the wearer of the boot or shoe, I provide a spring 4 which comprises a longitudinally curved forwardly extending arm 5, a depending offset portion 6 and a rearwardly extending horizontally disposed arm 7. The arm 5 of the spring is embedded in the upper side of the arch support-

ing arm 2 and secured thereto and to the under side of the shank of the boot or shoe by the nails 8 which secure the layers of the leather that constitute the said arm 2 together, the said nails passing through openings with which the said spring arm 5 is provided. The depending offset portion 6 of the spring is embedded in the heel or in the layers of leather constituting the same, at the point where the arm 2 joins the heel, the layers of leather having an opening formed 65 therein for the reception of the said offset portion, as shown. The rearwardly extending arm 7 of the supporting and reinforcing spring lies between two of the layers of leather and is secured in place by one of the 70 nails 9 which secures the layers constituting the heel together. Hence the reinforcing spring device is entirely concealed.

Having thus described the invention, what is claimed is:—

1. A heel for boots or shoes provided with a forwardly extending arm to bear under the shank to support the arch of the foot, and a spring to reinforce and render said arm elastic, said spring comprising a forwardly extending downwardly curved arm embedded on the said arch supporting arm near the upper side thereof, a vertical downwardly extending offset portion at the rear end of said spring arm embedded in the heel and a rearwardly extending arm at the lower end of said offset portion and also embedded in the heel.

2. A heel for boots or shoes made up of layers of material and formed with a forwardly extending arch supporting arm and further provided with a reinforce spring having a forwardly extending downwardly curved longitudinal spring arm in said arch supporting arm and lying between certain of the layers of the arch supporting arm, a vertical downwardly extending offset portion disposed in the heel and passing through certain of the layers of material and a rearwardly extending arm at the lower end of said offset portion disposed between two of the layers of material.

In testimony whereof I affix my signature in presence of two witnesses.

JOHN P. NAUGHTON.
